CLAIM

The ornamental design for the syringe for endoscope, as shown and described.

DESCRIPTION

FIG. 1 is a front, bottom and left side perspective view of the syringe for endoscope, showing a my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a cross sectional view thereof, taken along the line 8-8 in FIG. 2; and,

FIG. 9 is an enlarged cross sectional view thereof, taken along the line 9-9 in FIG. 2.

The broken lines showing portions of the syringe for endoscope are for illustrating environmental structure, and form no part of the claimed design.
